PAPER ROLL RACK

Fred Mellor, Shreveport, La., assignor of one-half
to Howard George, Benton, La.

Application February 11, 1944, Serial No. 522,201

3 Claims. (Cl. 242—55.2)

My invention relates to paper roll racks and more especially to paper roll racks adapted to be tilted into positions to facilitate the placing of rolls of paper into the rack.

A roll of wrapping paper such as the kind used by merchants for the wrapping of merchandise is quite heavy, almost too heavy for a lady clerk to lift in loading prior art types of paper roll racks with stationary bearings in elevated positions. To load such prior art types of paper roll racks with a roll of paper it is necessary for the clerk to hold up the heavy roll of paper between the bearings and in alignment with the bearings while he jockies the ends of the axle into the bearings.

An object of my invention is to provide a paper rack support that is adapted to be tilted into a loading position to receive a roll of paper resting on a counter or other surface that my paper roll rack is mounted on.

Another object of my invention is to provide a paper roll rack with guide members adapted to guide the ends of axle member supporting the paper roll into the axle bearings of my paper roll rack.

Other objects and advantages of my invention will appear from a reading of my detailed description to follow of the paper roll rack embodying my invention shown in my accompanying drawing.

In the drawing:

Figure 1 is an elevation view of a paper roll rack embodying my invention.

Figure 2 is a plan view of the paper roll rack shown in Figure 1, shown in a tilted or loading position, and,

Figure 3 is a side elevation view of the paper roll rack shown in a tilted or loading position.

The paper roll rack illustrated in the drawing is shown mounted on a counter C and supplied with a paper roll R.

In the drawing 1 designates foot plates secured to the counter C by screws 2. The foot plates 1 are provided with notches 3 in their upper edges for purposes to be explained later.

A pair of standards 4 provided with feet 5 are pivotably mounted on the foot plates 1 at the toe ends of the feet 5. By this arrangement of mounting the standards 4 can be tilted to the prone positions shown in Figures 2 and 3 or raised to the operating position shown in Fig. 1. The feet 5 on the standards 4 hold the standards 4 in the vertical position or operating position under the weight of the paper roll R, shown mounted on the axle A, because the force of gravity F (see Fig.

3) acting through the center of gravity acts at a distance forward of the pivot points P at which the standards 4 are attached to the foot plates 1. I provide clamping screws 6 in threaded engagement with the standards 4 as a means for clamping the standards 4 to the footplates 1 in the operating position to prevent my paper roll rack being accidentally pushed over on the counter C. The shanks of the clamping screws 6 are positioned in the standards 4 so as to fall into the clamping notches 3 mentioned above when the standards 4 are brought into the upright or operating position. The standards 4 of my paper roll rack are joined together at their tops by means of a head board 9. A paper cutter generally designated by numeral 10 is pivotably attached to the head board 9 by spring hinges 13. The blade 11 of the paper cutter 10 is joined to the outer ends of the curved arms 12. This paper cutter 10 operates in the same manner as do the paper cutters incorporated in prior art paper racks.

The axle A supporting the paper roll R is made of size in length and diameter such that its ends loosely fit into U shaped axle bearings 8 attached to the innersides of the standards 4.

The description of the illustrated paper roll rack embodying my invention thus far recited, defines a practical, convenient, workable paper roll rack that fulfills the first object of my invention. The reader can easily see that even without the use of the lifting guides 7, to be described later, the ends of the axle A supporting the paper roll R can be easily moved into the U shaped axle bearings 8, when the U shaped axle bearings 8 are lifted into horizontal alignment with them by merely rolling the paper roll R on the counter C.

My inventive concept in a paper roll rack, however, goes further than the construction thus far described, in that I provide lifting guides 7 positioned in alignment with the U shaped axle bearings 8. By means of the lifting guides 7 the operator may lift a paper roll R on an axle A from a position on a counter, as seen in Figure 2 or Figure 3 of the drawing where the ends of the axle A extend crosswise of and above the guides 7, to an elevated position such as shown in Fig. 3 where the ends of the axle A are seated in the U shaped axle bearings 8 merely by lifting up the head board 9 and swinging the standards 4 into an elevated position. To bring the roll R into proper position to allow the guides 7 to contact the ends of the axle A, roll R should be rolled on the counter C into a diagonal position with respect to the same at a location where the guides

7 may be lowered past the ends of the axle A. When the guides 7 are so lowered, the position where the head board 9 rests on the counter C the roll R should then be turned on the counter C to bring the ends of the axle A over the guides 7. When the lifting guides 7 attached to the standards 4 are being swung upwardly while in contact with ends of the axle A to an angular position such as shown by the dotted lines in Fig. 3, the force of gravity acting on the paper roll R supported by the axle A, the ends of which rest on the guides 7, causes the ends of axle A to roll down the guides 7 into the U shaped axle bearings 8.

My paper roll support can be made out of the same kind of iron or other material heretofore used in the construction of prior art paper roll racks. The paper cutter head board 9, for the sake of economy, can be made out of wood. The foot plates 1 and the standards 4 can be fabricated from angle iron members if desired, or they may be cast in accordance with well known prior art manufacturing practices.

Having thus described my invention, I claim:

1. A paper roll rack comprising a base means adapted to be fastened to a counter or the like, a paper roll holding frame mounted on the base means and adapted to hold a paper roll in an elevated position above the counter or the like, the paper roll holding frame including a pair of standards extending in spaced parallel relationship from the base means, each of said standards being provided with a U shaped bearing having an opening located at a medial portion of the length of the standard adapted to receive the end of an axle supporting a paper roll, each of the standards being provided with a guide member in alignment with the rear wall of its U shaped bearing, the guide members being adapted to guide the ends of the axle into the U shaped bearings, each of the standards being pivoted to the base means to permit the paper roll holding frame to be revolved to a position where it contacts the counter or the like, whereby to facilitate the placing of the ends of the paper roll supporting axle in the U shaped bearings.

2. A paper roll rack comprising a base means

adapted to be fastened to a counter or the like, a paper roll holding frame mounted on the base means and adapted to hold a paper roll in an upright position above the counter or the like, the paper roll holding frame including a pair of standards extending in spaced parallel relationship from the base means, each of said standards being provided with a U shaped bearing having an opening located at a medial portion of the length of the standard and adapted to receive the end of an axle supporting a paper roll, each of the standards being provided with a guide member in alignment with the rear wall of one of the U shaped bearings, and adapted to guide an end of the axle into a U shaped bearing, each of the standards being pivotably mounted on the base means whereby the paper roll holding frame may be revolved to a position where it contacts the counter or the like to facilitate the placing of the ends of the paper roll supporting axle in the U shaped bearing, one of the standards being provided with a foot member adapted to hold the paper roll holding frame in an upright position and a clamping means adapted to clamp a standard in an elevated position to the base means.

3. A paper roll rack comprising a base means adapted to be fastened to a counter or the like and a paper roll holding frame mounted on the base means adapted to hold a paper roll in an elevated position above the counter or the like, said paper roll holding frame including a pair of standards extending in spaced parallel relationship from the base means, each of said standards being provided with a U shaped bearing on its inner side, each of said standards being provided with a guide member in alignment with the rear wall of one of the U shaped bearings, said guide member being adapted to guide an end of an axle into said U shaped bearing, each of said standards being provided with a foot member adapted to hold said paper roll holding frame in an upright position under the weight of a paper roll supported by said paper roll holding frame, said standards being pivotably attached to the base means at the toe ends of the foot members.

FRED MELLOR.
